UNITED STATES PATENT OFFICE.

GEORGE H. HART, OF WEST HARTFORD, CONNECTICUT.

ELECTRIC SWITCH.

1,139,278.

Specification of Letters Patent. Patented May 11, 1915.

Application filed December 31, 1914. Serial No. 879,821.

To all whom it may concern:

Be it known that I, GEORGE H. HART, a citizen of the United States, residing at West Hartford, Hartford county, State of Connecticut, have invented certain new and useful Improvements in Electric Switches, of which the following is a full, clear, and exact description.

My invention relates to improvements in electric switches and has for its object to produce a new and improved snap switch which is simple in construction and easy to manufacture and can be easily made of small dimensions.

15 A further object of my invention is to produce a push button switch of such a character.

The following is a description of an embodiment of my invention, reference being 20 had to the accompanying drawings, in which,—

Figure 1 is a side elevation of the switch complete, inclosed in its casing. Fig. 2 shows a vertical section through the casing 25 with one-half of the base and contact carried thereby removed. Fig. 3 shows a side elevation of the removed portion of the base and its contact. Fig. 4 shows an enlarged section of the switch without the casing, on 30 the line 4—4 of Fig. 2. Fig. 5 shows an enlarged detail of the switch-arm and push buttons, the push buttons being shown in section.

Referring more particularly to the drawings, 1 is the casing having end caps 2—2' provided with insulating bushings 3—3'.

4—4' are the two separable halves of the base. Mounted on the two halves of this base are stationary contacts 5—5' each 40 consisting of two spring members having separable jaws the mouths of which are flared so as to permit the easy entering of the switch-blades.

6 is a screw passing through the base portion 4 and entering the contact 5, and 6' is a similar screw passing through the base portion 4' and entering the contact 5'. These screws 6—6' form terminals for connecting the ends of the circuit wires. Inclosed in a 50 longitudinal opening, part of which is formed in each half of the base, is a hollow sliding actuating member the ends of which, 7—7' constitute push buttons. A central portion of this member is provided with a slot 8 and mounted in this slot is the lower

end of a switch-arm 9 having two peaked cam surfaces 10—10'.

11 is a pivot passing through the lower end of the switch-arm, and through the actuating member so as to connect the switch-arm to the actuating member in such a manner that it has a movement of oscillation relatively thereto about the pivot 11.

12—12' are balls inclosed in the ends of the actuating member and 13—13' are 65 springs tending to force those balls toward the center and causing them to engage with the cam surfaces 10—10'.

14—14' are switch-blades forming a part of the switch-arm 9 and electrically connected 70 together but insulated from the main portion of the switch-arm, by insulating washers 15. The main portion of the switch-arm is provided with bearing surfaces 16—16' which extend beyond the front and rear faces 75 of the switch-blades 14—14', and constitute shoes for engaging bearing surfaces 17—17' carried by the respective halves of the base.

The operation of the switch is as follows: When the parts are in the position shown in Fig. 2 pressure upon the push button 7 causes the actuating member to move to the left carrying the pivot 11. The shoe 16 bearing against the surface 17 prevents the upper end of the switch-arm from moving to the left and therefore causes the cam surface 10—10' to move until their peaks pass the balls 12—12', whereupon the springs 13—13' throw the balls toward the center and cause the switch-arm to move with a snap action toward the right into engagement with the stationary contacts, 5—5' forming an electrical connection between them. When the switch is in closed position, 80 pressure upon the push button 7 causes the actuating member to move to the right, whereupon the shoe 16' engaging the surface 17' prevents the upper end of the switch-arm from moving to the right and causes the cam surfaces 10—10' to move in the opposite direction from that above described, until the high points pass the balls 12—12', whereupon the springs 13—13' acting through the balls cause the switch-arm 85 to oscillate to the left relatively to the actuating member and withdraw from the contact members 5—5' opening the circuit.

I preferably use two cam surfaces 10—10' and two balls 12—12' and springs 13, 13', in which case the actions of the springs 90

2
 13—13' supplement each other and furthermore produce a somewhat balanced pressure against the lower end of the switch-arm and reduce the strain upon the pivot 11. The bases are provided with lateral extensions 18—18' the ends of which are separated so as to permit the passage of the shank of the switch-arm 9. They serve to separate to a considerable extent the engaging portions of the contacts 5—5' and the switch-blades 14—14' from the actuating mechanism and inclose those portions in a small inclosure. The casing 1 is provided with slots 19—19' into which the push buttons 7—7' enter as the assembled base and actuating parts are inserted in the casing. The casing is also provided with an insulating lining 20, while the caps are provided with insulating linings 21—21'. The base portions 4—4' are counterparts of one another, the passages 22—22' being left at each end of the dividing portions 18—18' so as to receive the upwardly extending portions of the contacts 5—5', one of these passages on each half of the base being occupied by such upwardly extending portion while the other is empty. I preferably make two of these passages since by reason of them the two halves of the base are exact counterparts requiring 30 but one set of molds and the unoccupied portions do not effect the operation of the switch. The two halves of the base are held together by screws passing through the holes 23—23'. The push buttons are provided with shoulders 24—24' which engage portions of the base, as shown in Fig. 2, and act as stops for the push buttons.

As will be evident to those skilled in the art, my invention permits of various modifications without departing from the spirit thereof or the scope of the appended claims.

What I claim is:

1. In an electric switch the combination of a base, stationary contacts thereon, an actuating member having a to and fro movement and carried by said base, an oscillating switch-arm pivoted to said actuating member and having a peaked cam, a spring-pressed body carried by said member and engaging said cam, said base having a surface located on the opposite side of said switch-arm from said stationary contacts and engaged by said switch-arm and causing its upper end to move relatively to said member in the direction of said contacts when said member is moved in the opposite direction.

2. In an electric switch the combination of a base, stationary contacts thereon, an actuating member having a to and fro movement and carried by said base, an oscillating switch-arm pivoted to said actuating member and having a peaked cam, a spring-

pressed body carried by said member and engaging said cam, said base having a surface located on the opposite side of said switch-arm from said stationary contacts and engaged by said switch-arm and causing its upper end to move relatively to said member in the direction of said contacts when said member is moved in the opposite direction, said switch-arm consisting of a main portion and blades insulated therefrom, said main portion having an extension which engages said surface on said base. 75

3. In an electric switch the combination of a base, stationary contacts thereon, an actuating member having a to and fro movement and carried by said base, an oscillating switch-arm pivoted to said actuating member and having a peaked cam, a spring-pressed body carried by said member and engaging said cam, and said base having two surfaces on opposite sides of said switch-arm and engaged by said switch-arm 80 so as to make its upper end move relatively to said member in a direction opposite to the movement of said member when said member is moved.

4. In an electric switch the combination of a base, stationary contacts thereon, an actuating member having a to and fro movement and carried by said base, an oscillating switch-arm pivoted to said actuating member and having a peaked cam, a spring-pressed body carried by said member and engaging said cam, and said base having two surfaces on opposite sides of said switch-arm and engaged by said switch-arm 85 so as to make its upper end move relatively to said member in a direction opposite to the movement of said member when said member is moved, said switch-arm consisting of a main portion and switch-blades insulated therefrom, the parts thereof which 100 engage said surface being oppositely extending portions of said main portion.

5. In an electric switch, the combination of a base, stationary contacts thereon, an actuating member having a to and fro movement carried by said base, an oscillating switch-arm pivoted to said member and having two oppositely extending peaked cams adjacent to the pivot, two spring-pressed bodies longitudinally movable within said actuating member and engaging said cams respectively, and means for preventing the upper end of said switch-arm from following the movements of said actuating member until the peaks of said cams have passed 115 said spring-pressed bodies. 120
